(57) **CLAIM**

We claim the ornamental design for a robotic mower body, as shown and described.

DESCRIPTION

FIG. 1 is a top front perspective view of a robotic mower body showing our new design;

FIG. 2 is a top rear perspective view thereof;

FIG. 3 is a top view thereof;

FIG. 4 is a bottom view thereof;

FIG. 5 is a right side view thereof;

FIG. 6 is a left side view thereof;

FIG. 7 is a front view; and,

FIG. 8 is a rear view.

In the drawings, any broken lines depict environmental subject matter only that forms no part of the claimed design.
